(57) **CLAIM**

We claim the ornamental design for a carrier for beer bottles, as shown and described.

DESCRIPTION

FIG. 1 is a perspective view of a carrier for beer bottles showing our new design.

FIG. 2 is an end elevational view thereof.

FIG. 3 is a front elevational view thereof.

FIG. 4 is a rear elevational view thereof.

FIG. 5 is a top plan view thereof; and,

FIG. 6 is a bottom plan view thereof.

The dashed lines in the drawings are for purposes of illustrating environmental structure as well as portions of the design that form no part of the claimed design.
